CLAIM

The ornamental design for an UNDERWATER SURVEYING DEVICE as shown and described.

DESCRIPTION

FIG. 1 is a rear, top, left perspective view of an UNDERWATER SURVEYING DEVICE showing our new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a rear elevation view thereof; and

FIG. 7 is front elevation view thereof.

The broken lines in the drawings depict portions of the Underwater Surveying Device which form no part of the claimed design.
